CLAIM

The ornamental design for a measuring device for monitoring the state of industrial machine, as shown and described.

DESCRIPTION

FIG. 1 is a front, top, and right side perspective view of a measuring device for monitoring the state of industrial machine showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines shown in the figures illustrate portions of the measuring device for monitoring the state of industrial machine that form no part of the claimed design.
